UNITED STATES PATENT OFFICE.

HENRY P. CLAUSEN, OF MOUNT VERNON, AND CHARLES L. GOODRUM, OF NEW YORK,
N. Y., ASSIGNEES TO WESTERN ELECTRIC COMPANY, INCORPORATED, OF NEW
YORK, N. Y., A CORPORATION OF NEW YORK.

TELEPHONE SYSTEM.

1,375,276.

Specification of Letters Patent. Patented Apr. 19, 1921.

Application filed December 28, 1918. Serial No. 268,662.

To all whom it may concern:

Be it known that we, HENRY P. CLAUSEN and CHARLES L. GOODRUM, citizens of the United States, residing at Mount Vernon, 5 in the county of Westchester and State of New York, and at New York, in the county of New York and State of New York, respectively, have invented certain new and useful Improvements in Telephone Systems, 10 of which the following is a full, clear, concise and exact description.

This invention relates to improvements in telephone systems and has particular reference to systems in which inter-office or inter-city trunk line circuits are used.

The common practice, in such systems, is to establish a connection between two remotely separated exchanges by joining together, through any suitable connecting 20 means at other intermediate exchanges, normally independent trunk circuits interconnecting said intermediate exchanges.

An object of this invention is to provide improved signaling means for such a system, 25 whereby the operators at the several exchanges may readily determine the condition of the various interconnecting trunk circuits and thereby expedite the establishment of a connection.

30 In accordance with this object, when all trunks connecting one exchange with any other are simultaneously busy a signal is operated to indicate such condition.

The inventive idea involved is capable of 35 receiving a variety of expressions, one of which, for the purpose of illustrating the invention, is shown in the accompanying drawing; but it is to be expressly understood that said drawing is employed merely 40 for the purpose of facilitating the description of the invention as a whole and not to define the limits thereof, reference being had to the appended claims for this purpose.

The drawing illustrates diagrammatically 45 a plurality of sectionalized trunk circuits for joining intermediate and widely separated exchanges and means at each exchange for indicating the status of the several circuits.

In the present embodiment of the invention, 50 the signals are operated over a common conductor interconnecting all exchanges and are controlled by means of synchronized distributors.

In the drawing four exchanges A, B, C and D are shown although it will be understood 55 that the number of these exchanges may vary in accordance with working conditions, exchange A is shown as consisting of jacks 1, 2 and 3 but the number of these jacks may also vary. Relays 4, 5 and 6 are associated 60 with the respective jacks 1, 2 and 3 and the armatures and contacts of said relays are connected in series so that when all of the jacks are busy, a ground for said armatures will be found at the armature of relay 4. A 65 trunk 7 is employed for interconnecting jack 1 with the jack 8 at exchange B and this latter jack has likewise associated therewith relay 9, the armature of which has ground connected thereto. The apparatus at ex- 70 change B also comprises another jack 10 for extending the trunk 7 to another trunk 11 leading to the jack 12 at exchange C, and said jacks 10 and 12 are provided respectively with relays 13 and 14. For extend- 75 ing trunks 7 and 11 to exchange D, a trunk 15 is employed for interconnecting jacks 16 and 17 at said exchanges and the respective jacks have relays 18 and 19 associated therewith. Exchange C further comprises 80 jacks 20 and 21 having relays 22 and 23 connected thereto, the jack 20 being connected directly to jack 2 at exchange A by means of trunk 24. Jack 21 at exchange C is connected to jack 55 at exchange D by means 85 of trunk 25, and associated with said jack 55 is a relay 26. Similarly, exchange B fur- 90 ther comprises jacks 27 and 28, and associated relays 29 and 30 and jack 27 is connected to jack 3 at exchange A by means of trunk 31, while jack 28 is connected to jack 32 and its associated relay 33 at exchange D by means of trunk 34.

The exchanges are provided respectively with synchronized distributors 35, 36, 37 95 and 38, which may be of any construction well known in the art, and which are all interconnected by a conductor 39 for controlling suitable signaling means at the various exchanges. These signaling means pref- 100 erably comprise lamps 40 and 41 at exchange A, lamp 42 at exchange B, lamp 43 at ex- change C and lamps 44 and 45 at exchange D and said lamps are operated in a manner to appear to indicate the condition of the 105 various interconnecting trunk circuits.

It is now believed that the invention will be fully understood from a detailed description of the operation thereof.

Should the operator at exchange A desire 5 to establish a connection to exchange D, the possibility of making a connection directly to exchange B over trunks 7 or 31 may be determined by individual signaling means (not shown) well known in the art and as- 10 sociated with the relays of jacks 1 and 3. If these signaling means indicate that trunks 7 and 31 are busy, then it will only be possible for the operator at exchange A to make connection directly to jack 20 at exchange C 15 over trunk 24. The condition of this trunk may also be determined by signaling means similar to that just referred to and connected to the terminals of said trunk. In a like manner, such signaling means may be em- 20 ployed for designating the condition of trunks which directly connect the various exchanges. If all trunks leading from exchange B toward exchanges C and D are busy, relays 13 and 30 will be energized in 25 a manner well known in the art and a circuit will be intermittently closed for relay 46 associated with lamp 41 at exchange A, said circuit extending from grounded battery, winding of relay 46, contact 47 of distrib- 30 utor 35, the wiper of said distributer, conductor 39, wiper of distributer 36, contact 48 thereof, front contacts and armatures of relays 30 and 13 to ground. Energization of relay 46 will establish a circuit for lamp 35 41 extending from grounded battery, front contact and armature of relay 46 and lamp 41 to ground. Flashing of this lamp will indicate to the operator at exchange A that a connection cannot be established with ex- 40 change D over trunks extending from jacks 10 and 28. Similarly should trunks connected to jacks 12 and 20 of exchange C be busy, relays 14 and 22 will be energized and ground will be placed upon contact 49 of 45 distributer 37, and lamp 41 will be lighted in the same manner as previously described, the relative position of contact 49 being the same as that of contacts 47 and 48 of the distributers 35 and 36. Should relays 18 and 23 50 at exchange C be energized, a ground will be placed upon contact 50 of distributer 37 and as the wiper thereof passes over said contact, a circuit will be closed for relay 51 at exchange A extending from grounded bat- 55 tery, winding of relay 51, contact 52 of distributer 35, wiper thereof, conductor 39, wiper 37, contact 50, front contacts and armatures of relays 23 and 18 to ground. Relay 51 will then energize and close a cir- 60 65 60 circuit for lamp 40 extending from grounded battery, front contact and armature of relay 51 and lamp 40 to ground. Flashing of this lamp will indicate to the operator at exchange A that trunk circuits extending from exchange C toward exchange D are busy.

If all trunks leading from exchange D are busy, relays 19, 26 and 33 will be energized and a ground will be placed upon contact 53 of distributer 38, which has a position corresponding to contact 50 of distributer 37 and through the medium of the wiper of distributer 38 and conductor 39, it will be obvious that relay 51 will be energized in the same manner as previously described and lamp 40 operated.

In the same manner, should the operator at exchange B desire to establish connection to exchange B, lamp 42 will indicate the condition of various trunks between said exchanges and will flash when relay 54 associated therewith is energized by a circuit which is closed when relays 18 and 23 at exchange C or relays 19, 26 and 33 at exchange D are contemporaneously energized. Also, lamps 44 and 45 at exchange D and lamp 43 at exchange C will be lighted to indicate to the operators at such exchanges that connections cannot be established to other exchanges should all the trunks leading thereto be busy. The lamps at said exchanges C and D are operated by the energization of the relays associated therewith, when the wipers of the several distributers pass over contacts upon which ground has been placed by the contemporaneous energization of relays at the various exchanges to which busy trunks are connected.

What is claimed is:

1. In a telephone system, a plurality of exchanges, a plurality of trunk circuits for establishing connections between said exchanges, means at each exchange for indicating the condition of trunk circuits interconnecting other exchanges, and means operating in synchronism for controlling the first named means.

2. In a telephone system, a plurality of exchanges, a plurality of trunk circuits for establishing connections between said exchanges, means at each exchange for indicating the condition of trunk circuits interconnecting other exchanges, a conductor connecting various exchanges, and means connected to said conductor and operating in synchronism to control the indicating means.

3. In a telephone system, two widely separated exchanges, intermediate exchanges, a plurality of trunk circuits for establishing connection between said exchanges, means at each exchange for indicating the condition of trunk circuits interconnecting other exchanges and means operating in synchronism for controlling the first named means.

4. In a telephone system, two widely separated exchanges, intermediate exchanges, a plurality of trunk circuits for establishing connection between said exchanges, means at each exchange for indicating the condition of trunk circuits interconnecting other

exchanges, a conductor connecting the various exchanges, and distributor connected to said conductor at said exchanges respectively, and operating in synchronism 5 to control said indicating means.

5. In a telephone system, a plurality of exchanges, a plurality of trunk circuits for establishing connections between said exchanges, relays associated with the terminals 10 of said trunk circuits, the contacts of the relays for corresponding terminals of all trunk circuits interconnecting certain exchanges being connected in series, means at each exchange for indicating the condition 15 of trunk circuits interconnecting other exchanges, and means operating in synchronism for controlling the first named means.

6. In a telephone system, a plurality of exchanges, a plurality of trunk circuits for 20 establishing connections between said exchanges, relays associated with the terminals of said trunk circuits, the contacts of the relays for corresponding terminals of all trunk circuits interconnecting certain exchanges being connected in series, means at 25 each exchange for indicating the condition of trunk circuits interconnecting other exchanges, a conductor connecting the various exchanges, and means connected to said conductor and operating in synchronism to control 30 said indicating means.

7. In a telephone system, widely separated exchanges, intermediate exchanges, a plurality of trunk circuits for establishing connection 35 between said exchanges, relays associated with the terminals of trunk circuits, the contacts of the relays for corresponding terminals of all trunk circuits interconnecting certain exchanges being connected in 40 series, means at each exchange for indicating the condition of the trunk circuits interconnecting other exchanges, and means operating in synchronism for controlling the first named means.

45 8. In a telephone system, widely separated exchanges, intermediate exchanges, a plurality of trunk circuits for establishing con-

nexion between said exchanges, relays associated with the terminals of trunk circuits, the contacts of the relays for corresponding 50 terminals of all trunk circuits interconnecting certain exchanges being connected in series, means at each exchange for indicating the condition of the trunk circuits interconnecting other exchanges, a conductor connecting the various exchanges, and means 55 connected to said conductor and operating in synchronism to control said indicating means.

9. In a telephone system, a sectionalized 60 trunk circuit, means associated with certain sections of said circuit for indicating the status of other sections, and means operating in synchronism for controlling the first 65 named means.

10. In a telephone system, a plurality of exchanges, a plurality of trunk circuits for establishing connections between said exchanges, means at each exchange for indicating the condition of trunk circuits interconnecting other exchanges, and means operating in synchronism for controlling the first 70 named means.

11. In a telephone system, a plurality of exchanges, a plurality of trunk circuits for 75 establishing connections between said exchanges, means at each exchange to indicate the condition of the trunk circuits interconnecting other exchanges, and a distributor at each exchange operating in synchronism 80 with distributor at the other exchanges to control said means.

12. In a telephone system, a sectionalized trunk circuit, means associated with certain sections of said circuit for indicating the 85 status of other sections and distributor operating in synchronism for controlling said means.

In witness whereof, we hereunto subscribe our names this 12th day of December A. D., 90 1918.

HENRY P. CLAUSEN.
CHARLES L. GOODRUM.
